UNITED STATES PATENT OFFICE.

HUBERT F. KRANTZ, OF BROOKLYN, NEW YORK, ASSIGNOR TO KRANTZ MANUFACTURING COMPANY, INC., OF BROOKLYN, NEW YORK, A CORPORATION OF NEW YORK.

SAFETY-SWITCH MECHANISM.

1,399,498.

Specification of Letters Patent. Patented Dec. 6, 1921.

Application filed August 5, 1918. Serial No. 248,330.

To all whom it may concern:

Be it known that I, HUBERT F. KRANTZ, residing at Brooklyn, in the county of Kings and State of New York, have invented certain new and useful Improvements in Safety-Switch Mechanism, of which the following is a specification.

This invention relates to a safety switch mechanism.

10 An object of the invention is to provide a safety switch mechanism having an over-load control associated therewith.

A further object is to so arrange the parts of the device that an element of the 15 over-load control constitutes a spark blow-out for the switch.

A further object is to provide an improved switch mechanism in which the switch blade will be automatically moved "off" upon the 20 occurrence of an over-load in the circuit and in which the switch blade will not remain in "on" position if moved to such position while an over-load or short circuit condition exists.

25 A further object is to provide a switch mechanism in which the over-load control elements are relieved of all strain while the switch is "on."

A further object is to provide manual control means for the switch adapted to move the switch "on" in which position the switch is held irrespective of the presence of the over-load controlling elements until moved "off" either by manual means or by action 35 of the over-load control.

A further object is to provide the switch with an operating handle and to so arrange the connections between the switch and the over-load control as not to require "off" 40 movement of the operating handle when the switch blade moves "off" in response to the operation of the over-load control.

A further object is to provide means for positively indicating whenever the switch 45 blade has been moved "off" by operation of the over-load control.

A further object is to provide means for causing the operating handle to move more or less out of its "on" position, that is, into 50 an intermediate position to thus constitute a definite indication whenever the switch blade moves "off" in response to the operation of the over-load control.

A further object is to provide, in the structure, auxiliary means for indicating when-

ever the over-load control operates to move the switch "off".

A further object is to provide a toggle operated switch, the toggle of which is adapted to move into "made" and "broken" positions 60 for operating the switch blade, and to provide an over-load control which is entirely free of all strain when the toggle is made, but which is adapted to "break" the toggle upon the occurrence of an over-load. 65

A further object is to provide, in the above combination, an over-load coil operable to attract a pivotally mounted armature for supplying the power to "break" the toggle, and to so arrange the parts as to 70 make the coil operative upon the armature at a point adjacent to the application of power by the armature.

A further object is to provide a casing for the mechanism, to provide a door for 75 giving access into the casing, and to provide the switch with a part which may be operated either by the door or the over-load control for moving the switch into the "off" position. 80

Other objects and aims of the invention more or less specific than those referred to above, will be in part obvious and in part pointed out in the course of the following description of the elements, combinations, 85 arrangements of parts and applications of principles, constituting the invention, and the scope of protection contemplated will be indicated in the appended claims.

In the accompanying drawings which are 90 to be taken as a part of this specification, and in which I have shown merely a preferred form of embodiment of the invention:

Figure 1 is a top plan view of a device 95 constructed in accordance with this invention.

Fig. 2 is a longitudinal sectional view taken substantially upon the plane of line II of Fig. 1.

Fig. 3 is a top plan view of the portion of 100 the structure shown in Fig. 2, but the cover plate being removed.

Fig. 4 is a transverse sectional view taken substantially upon the plane of the line IV of Figs. 1 and 2. 105

Figs. 5, 6 and 7 are diagrammatic views corresponding to a portion of Fig. 2 and illustrating the parts of Fig. 2 as they appear in different positions, and

Fig. 8 is a diagrammatic view illustrat- 110

ing a modified arrangement adapted for use in connection with a 3-wire system.

Referring to the drawings for describing in detail the structure which is illustrated therein, the reference character L indicates a casing for containing the current-carrying and moving parts of the device. This casing may be made up in any suitable manner and of any appropriate material, but it is preferably made of sheet metal shaped to form a back wall 1, top wall 2, bottom wall 3, opposite side walls 4, and a front wall, or cover plate 5. These walls, wherever necessary, may be connected together by suitable angles, or the like, as 6, into which screws, or rivets 7 engage.

Within the casing is arranged a base plate 8 of suitable insulating material such as slate, or the like, and between the front face 20 of this base plate and the rear surface of the cover plate 5 extends a pair of wall members 9, said wall members being rigidly connected in position by means of bolts, or screws 10 which engage flanges 11 formed 25 upon the wall members 9.

The wall members 9 are arranged parallel with the side wall members 4 and are spaced from each other and from said side wall members so that they serve as partitions defining a central space 12 between them and a pair of channels 13 and 14 between themselves and the side walls 4.

The switch device is arranged within the central space 12 and comprises a carrier 15 which extends transversely across said space and has pivot extensions 16 engaging within the bearing apertures 17 formed in said wall members 9.

The carrier 15 is of the same general construction as is shown and described in Patent No. 1,248,415, granted to me Nov. 27, 1917. That is, it includes a pair of clamp plates, as 18, between which the switch blades 19 and 20 are rigidly held in insulated spaced relation, sections of insulating material, as 21, being interposed between the blades and the clamp plates for insulating the blades from the clamp plates.

The blades are held by their mid portions 50 and opposite ends of each of the blades project laterally from the carrier into co-operative relation with fixed contacts within the casing. The two ends of the blade 19 co-operate with fixed contacts 22 and 23, 55 while the two ends of the blade 20 co-operate with the fixed contacts 24 and 25. One, or more springs, as 26, engage between the carrier and the wall members 9 to normally urge the carrier into position with the switch 60 blades both held "off."

An operating handle 27 is provided for manually moving the switch blades at will. This handle is pivotally mounted upon a pivot pin 28 which is carried by a supporting bracket or frame 29 within the casing,

the outer end of the handle projecting through an opening 30 in the cover plate 5 to a position of accessibility exteriorly of the casing. A toggle made up of links 31 and 32 is connected to be operated by the handle for moving the carrier in response to the movements of the handle. The link 31 is pivotally mounted upon the pivot pin 28 and is connected to the link 32 by a pivot pin 33 forming the knee of the toggle. The opposite end of the link 32 is pivotally connected, as at 34, to an extension 35 which projects laterally from the carrier 15.

Whenever the toggle is made, the blades stand "on." As soon as the toggle is broken 80 the spring 26 drives the blades quickly into "off" position.

The link 31 is provided with an extension 36 which is arranged to engage against a set screw 37 carried by the cover plate 5 for limiting movement of the toggle in the "made" direction. The link 31 is also provided with an extension 38 for engaging against the under surface of the cover plate 5 to limit movement of the toggle in the "broken" direction.

One, or more light springs 39 are mounted upon the pin 28 and are adapted to engage between the operating handle and the frame 29 for normally retaining the operating handle in its elevated position, as shown in Fig. 2. The handle 27 is provided with a shoulder 40 which is adapted to engage against a surface portion 41 of the link 31 when the handle is drawn downwardly to 100 "break" the toggle, said shoulder being positioned to press against the surface 41 only when the handle is in a position near its lowest extreme of movement, the engagement being maintained only sufficiently long to cause the pivot 33 to pass center. The spring 26 will then complete the toggle movement to full "off" position.

The set screw 37 is adjustable so as to alter the degree of movement of the pivot 33 beyond center when the toggle is "made," thus taking care of any inaccuracies of manufacture which might occur. Since, of course, the farther the pivot 33 moves beyond center when the toggle is "made," then the more power is required to "break" the toggle, the movement of the screw 37 will accomplish an adjustment of the amount of power required to "break" the toggle.

Within the casing is arranged suitable fuses, or the like, as 42, and the cover plate 5 is therefore provided with a door 43 which is pivotally connected, as at 44, for giving access into the casing at will.

In order that the door may not be opened while the fuses, or other parts accessible through the door opening, are live, the door is provided with a heel piece 45 projecting beyond the pivot 44 and adapted to move 130

through an opening 46 in the adjacent portion of the cover plate for engaging against the extension 36 of the toggle link 31 to "break" the toggle upon opening movement 5 of the door. A slight opening movement of the door will move the pivot 33 of the toggle backwardly past center and the spring 26 will complete the "off" movement and place the switch blades free of the contacts so 10 that the fuses become "dead".

Between the contact 23 and the adjacent fuse 42 is arranged a coil G through which current must travel between said contact and fuse. Within the coil is a core 47, and 15 above the core is a movable armature H which is pivotally mounted, as at 48, in a suitable supporting frame 49 carried by the base plate 8. The armature is weighted, as at 50, so as normally to stand away from 20 the end of the core. A stop 51 is provided upon the frame 49 for limiting movement of the armature away from the core. The stop 51 is preferably arranged to move in 25 a slot 52 provided in the arm 49 so that the extent of movement of the armature away from the core may be adjusted at will. If 30 desired, a set of graduations 53 may be provided adjacent the slot for determining the position at which the stop should be set in order that a given amount of current in the coil G may be required to attract the armature.

A bell-crank lever 54 is pivotally mounted at its midpoint upon the extension 36 of 35 the toggle link 31. One leg of the bell-crank, as 55, is disposed in the path of movement of the free end of the armature H and the other end, as 56, of the bell-crank is disposed to coöperate with a pawl 57 which is 40 also pivotally mounted upon the extension 36 and which, in turn, engages the operating handle 27.

With the parts in the position as shown in Fig. 2, the end 56 of the bell-crank lever 45 engages a shoulder 58 of the pawl and holds the end 59 of the pawl against a surface portion 60 of the operating handle 27, which surface 60 is substantially concentric with the pivot pin 28. In this position also the 50 end 59 of the pawl stands in position beneath a shoulder 61 formed upon the operating handle.

A light compression spring 62 is provided for urging the bell-crank lever and the 55 pawl into the position indicated, and a stop 63 is provided for limiting movement of the pawl out of this position relative to the extension 36.

The end of the armature H is fitted with 60 an anti-friction roller 64, and the end 55 of the bell-crank lever provides a surface 65 along which the roller 64 may travel in its initial movements toward the core 47. The 65 surface 65 is arranged at such an angle relative to the pivot 48, and the position of the

roller, that movement of the roller along said surface will cause the bell-crank lever to swing slightly about its pivotal support 66 and disengage from the shoulder 58 of the pawl 57. The pawl will thereupon fall 70 away from the surface 60 and stand free of the shoulder 61. (Fig. 5.)

Beyond the surface 65 of the bell-crank is a curved shoulder 67 over which the roller 64 must pass before movement of the armature is arrested by striking the core 47. As the roller passes on to the shoulder 67, the movement of the bell-crank around the pivot 66 will be arrested by engagement of the bell-crank with the stop pin 63, and thereafter, as the roller travels over the shoulder 67 and on to the surface 68 beyond said shoulder, any movement imparted to the bell-crank by the roller, will be accompanied by a corresponding movement of the 85 link 31 as if said bell-crank and link were an integral member.

The operating handle 27 may meanwhile stand stationary and the end 59 of the pawl will ride idly over the surface 69 of said 90 handle.

If desired, the armature H may be provided with an adjustable set screw 70 for engaging an extension 71 of the arm 55 of the bell-crank for improving the operation 95 of the device. The provision of this adjustable set screw becomes important when, for any reason it becomes desirable to cause movement of the link 31 before the roller 64 reaches the shoulder 67. A very accurate 100 adjustment of operation of the parts may thus be obtained.

In the structure as illustrated the position of the coil G, with its core 47, is between the pivot 48 and the roller 64 being somewhat 105 nearer to the roller than to the pivot. By this means a very powerful pull is felt by the armature for applying the necessary force to break the toggle.

It is believed that the operation of the 110 over-load device may now be fully understood, especially when taken in connection with the diagrammatic illustration Figs. 5, 6 and 7.

Supposing the parts to be in the position 115 as shown in Fig. 2: If an over-load occur in the circuit so that the armature H is drawn suddenly against the core 47, the initial movement of the roller 64 will be along the surface 65 approximately to the shoulder 120 67, thus bringing the bell-crank lever against the stop 63 and allowing the pawl 57 to fall away from the shoulder 61, all as shown in Fig. 5.

The final movement of the armature H 125 will press down on the shoulder 67 and cause the link 31 to rotate about the pivot 28 so that the knee joint 33 of the toggle will pass center, as shown by the full lines in Fig. 6, and the toggle thereupon immediately snap 130

into the full "off" position, as shown by the dotted lines in said figure.

As soon as the bell-crank lever passes out of engagement with the roller 64, the spring 62 urges the bell-crank away from the stop 63 and causes the end 56 of the bell-crank to press upon the relatively inclined surface 72 of the pawl and thereupon urges the end 59 of the pawl against the surface 69 of the 10 operating handle.

In order now to return the toggle to "made" position, the operating handle is swung downwardly into the position as shown in Fig. 7, whereupon the spring 62, 15 acting through the bell-crank lever, will cause the pawl to snap beneath the shoulder 61 of the operating handle. An upward movement of the operating handle, now, will bring the shoulder 61 against the pawl 20 and return the toggle to its "made" position.

It should be particularly noted that, if when the toggle is being "made," as just described, the conditions which caused the over-load, current in the coil G still exist, 25 then said coil will become "live" again as soon as the switch blade reaches the contacts, that is, even before the toggle reaches its final straightened position, and the armature H will be held against the core so that 30 as the toggle approaches its final position the arm 55 of the bell-crank will engage the roller 64 and be pressed back thereby so that the pawl 57 will disengage from the handle, whereupon the spring 26 will immediately 35 snap the blades "off" in exactly the same manner as has already been fully described.

It will be seen therefore that in order for the over-load control to successfully perform its function of moving the switch blades 40 "off," it is not necessary for the handle 27 to move from its "off" position. The operator's hand may still be on the handle holding it up, or the handle may be tied, or otherwise held against movement, as by some foreign 45 object resting against it. The over-load control disengages the switch blades from the handle and then proceeds to release the blades.

As illustrated, the blades are preferably 50 made up in laminated form, as shown and described in my pending application Serial No. 175,192, filed June 16, 1917, and, as fully set forth in said copending application, are 55 adapted to flex against the contacts when the toggle is made. It will be seen, therefore, that the blades themselves coöperate with the springs 26 to hold the toggle in "made" position and to cause the blades to snap "off" the instant the toggle is "broken." 60 The extensions 90 also act as auxiliaries in this connection.

If desired the spring, or springs 39 may be of just sufficient strength to counteract the force of gravity in the handle 27 and 65 serve thereby for maintaining the handle 27

in any position of elevation to which it may be manually or otherwise moved. By this arrangement, and by providing a slight frictional engagement of the handle with the link 31, a very desirable result may be attained, namely, of causing the handle to move downwardly and to maintain an intermediate position whenever the switch moves "off" under the operation of the over-load control. In order to produce this result the 75 frictional engagement of the link 31 with the operating handle need be only very slight so that as the link 31 rotates into "off" position only a small portion of the movement of said link will be transmitted to the 80 handle.

It follows, therefore, that the operating handle in an intermediate position constitutes an indication that the over-load control has operated.

While it has been above stated that the roller 64 is adapted to engage the surface 65 for producing the initial movements of the bell-crank 54, nevertheless it will be understood that satisfactory results may be attained by bringing the roller first into engagement with the surface 67. The initial movements of the bell-crank would then be produced by movement of the roller for a given distance over the surface 67 toward 95 the surface 68, and further movement of the bell-crank would be produced as the roller moves on to the surface 68. In this instance the adjusting screw 70 may, if necessary, be employed for engaging the extension 71 to 100 cause the final movement of the bell-crank prior to the breaking of the toggle and just before the armature H strikes the core G.

The main line, or power wires, as 73 and 74, lead into the casing preferably from 105 opposite sides, as shown in Fig. 1, and are connected respectively with the contacts 22 and 24. The point of connection is adjacent to the cover plate 5 so that the incoming wires are held away from the rear portion 110 of the casing. The walls 9 carry angle brackets 101 which serve to support an insulating plate 75 at the inner surface of the cover plate to which the contacts 22 and 24 are connected, and to which, in turn, the incoming wires 73 and 74 are connected by means of suitable bolts 76.

The circuit wires for connection with a motor, or other device, are indicated at 77 and 78. These are connected with the contacts 23 and 25 respectively through fuses, and the connection with the contact 23 being through the intervening coil G. The wires 77 and 78 may lead out of the casing, at any desired point, but preferably extend directly 125 through the bottom wall 3 thereof.

The casing is fitted with a partition 79 at its upper end defining a space above it within the casing which is divided by a partition 80 providing two compartments 81 and 82 130

separated from each other and from the main portion of the casing. Within the compartment 81 is arranged a lamp 83 which is connected by wires 84 with the main line contacts 22 and 24. The front wall of the casing over the lamp 83 is formed with an opening closed by a piece of glass, as 85, upon which is inscribed the word "Power." Within the compartment 82 is arranged a lamp 86 which is connected by wires 87 with the contacts 88 of the circuit wires 77 and 78. The front wall of the casing over the lamp 86 is formed with an opening closed by a piece of glass, as 89, upon which is inscribed the word "Circuit."

The position of the wires within the passageways 13 and 14 avoids possibility of injury to the wires or of interference with the operation of the mechanism between the walls 9. It should be noted, of course, that any other wires, as for instance the wires 73-74 or 77-78, might traverse the passageways 13 and 14, if the point of entrance of said wires into the casing require, and that the walls 9 will protect these wires also and prevent them from interfering with the operation of the switch mechanism between the walls 9.

It will be seen, by this arrangement, that the lamp 83 beneath the word "Power" will be maintained illuminated at all times while current is present in the wires 73 and 74, whether the switch be "on" or "off." Any "breaking" of the circuit which would extinguish the lamp 83 would necessarily be above the switch.

The lamp 86 beneath the word "Circuit" would only be illuminated while the switch is "on" and then only while the connection through the fuses 42 is maintained. Failure of the lamp 86 to maintain its light, except while the switch handle is in its lowered or "off" position will indicate either a blown fuse or the existence of an over-load condition which has thrown the switch "off" through the action of the armature H, or both.

The wires 84, being attached to the contacts 22 and 24, are, like the wires 74, held away from the rear portion of the casing. The wires 87, which are attached to the contacts 88 at the rear lower portion of the casing, extend through the passageways 13 and 14 and pass spaced between the wires 73, 74 and 84. By this arrangement wires of opposite polarity are easily kept spaced apart sufficiently so likelihood of short circuit is reduced.

The position of the coil G constitutes it as a blow out means for the spark which might occur whenever the switch blades move away from the contacts 23 and 25.

In order to localize the spark at the contacts 23 and 25, the switch blades are preferably provided with extension pieces 90 at

their ends which engage the contacts 22 and 24. These extension pieces are flexible and are bent so as normally to extend beyond the plane of the contact surfaces of the blades, as clearly shown in Figs. 6 and 7. 70 They are thus adapted to maintain engagement with the contacts 22 and 24 until after the circuit has been first broken at the contacts 23 and 25.

It will be understood that the extension pieces 90 might be provided at both ends of the blade if desired, and that they are here shown at only one end of the blade as a simple expedient for illustrating means to maintain contact at said end after the other 80 end has moved "off."

As a convenient means for providing the bearings for the extensions 16 of the switch blade carrier 15, said bearings comprise apertures formed through the walls 9 and 85 backed by saucer shaped members 91 which are fixed to the walls 9 to receive end thrust from the extension 16 and to thereby retain the extensions 16 against displacement. Whenever it is desired to remove the carrier 90 15, one of the plates 91 may be detached, by the simple expedient of removing its retaining screws 92, whereupon the carrier may be shifted endwise, detached from the opposite bearing, and then shifted in the opposite 95 direction to detach from the first bearing.

The extensions 16 are formed with slots 93 longitudinally therein into which one end, as 94, of the springs 62 engage, the opposite ends of the springs engaging against pins, as 100 95, fixed to the walls 9. This provides an efficient and easily assembled means of retaining the springs in operative position.

The frame, or bracket 29 for supporting the pivot pin 28 is preferably made of such 105 size as to extend into connection with the base plate 8. It is preferably formed of a single piece of sheet metal bent into U-shape. The connecting part of the U lies flat against the base plate 8 and is connected thereto by 110 suitable screws, or bolts 96. Flanges 97, formed at the ends of the legs of the U, are fixed to the inner surface of the cover plate 5, as by means of screws, or rivets 98. This frame, therefore, serves not only as a means 115 to support the pivot pin 28 from the cover plate, but it also constitutes a rigid brace, or reinforcing element for the cover plate at the point where strain is applied from the operating handle 27 and from the blades. 120

The inner end portion of the operating handle is preferably bifurcated, providing two halves, or legs 99 and 100 spaced apart to receive the link 31 between them. The provision of the two legs 99 and 100 each 125 with a bearing aperture engaging the pivot pin 28, provides a broad pivot bearing for the operating handle, and this, together with the engagement of the link 31 between the legs, avoids any undue lateral movement 130

of the operating handle. Engagement of "on" and "off" movements respectively of the switch blade, and an over-load control for the switch blade, including means to move the operating handle into an intermediate position upon operation of said over-load control. 70

5 In the modification Fig. 8, a 3-wire system is illustrated. In this instance the two outside wires are provided with coils G. In 10 other respects the mechanism is substantially the same as has already been described, each coil G, of course, being provided with an armature connected for operating upon the bell-crank 54.

15 As many changes could be made in this construction without departing from the scope of the invention as defined in the following claims, it is intended that all matter contained in the above description, or shown 20 in the accompanying drawings, shall be interpreted as illustrative only and not in a limiting sense.

Having thus described my invention, what I claim as new and desire to secure by Letters Patent is:—

25 1. A switch mechanism comprising a movable contact member, a stationary contact member therefor, a toggle mechanism for actuating the movable contact member, a 30 handle for operating the toggle mechanism and movable independently thereof, a latch mounted on the toggle mechanism for connecting the operating handle to the toggle mechanism and an overload mechanism for 35 controlling the latch and the toggle mechanism.

2. A switch mechanism comprising a movable contact member, a stationary contact member therefor, a freely movable rotatable 40 operating handle, a toggle mechanism for the movable contact member pivoted for rotation about the axis of rotation of the operating handle, and a latch for operatively connecting the operating handle to the toggle mechanism.

45 3. A switch mechanism comprising a switch blade, a stationary contact member, a toggle mechanism, an overload device, connecting means between the toggle mechanism and the overload device, and an operating handle having frictional engagement with the toggle mechanism whereby movement of the toggle mechanism in one direction causes movement of the handle, said 50 connecting means being adapted to positively connect the handle to the toggle mechanism under predetermined conditions.

55 4. A safety switch mechanism comprising a switch blade movable into "on" and "off" 60 positions, a contact for the switch blade, an operating handle for the switch blade also movable into "on" and "off" positions, connections between the operating handle and the switch blade whereby "on" and 65 "off" movements of the handle will produce

75 5. A safety switch mechanism movable into "on" and "off" positions, a contact for the switch blade, a casing for containing said switch blade and contact, the casing 80 having a door providing entrance thereto, releasable retaining means to hold the switch blade "on," an over-load control, and means whereby said retaining means may be released either by said over-load control or by an opening movement of the door.

6. A safety switch mechanism comprising a casing, a pair of switch blades therein movable into "on" and "off" positions, contacts for said switch blades, an operating 85 handle for the switch blades extending exteriorly of the casing, connections between the operating handle and the switch blades to operate the switch blades from said handle, partitions within the casing defining a 90 pair of independent compartments, a lamp in each of said compartments, main line conductors extending into the casing adapted to be connected with the switch blades, connections from said main line conductors to 95 one of said lamps, branch line conductors extending into the casing being connected to said contacts, connections from said branch line conductors to the other lamp, one wall of the casing having a pair of openings, 100 therethrough adjacent said lamps, and means in said openings through which the light of the lamps may penetrate.

7. A safety switch mechanism comprising a switch blade movable into "on" and "off" 105 positions, a contact for the switch blade, an operating handle for the switch blade, connections between the operating handle and the switch blade whereby to move the switch blade in response to the movements of the 110 handle, and an over-load control for the switch blade, said over-load control comprising means operable to disconnect the switch blade from the handle and to thereafter actuate the connections to effect movement of the switch blade without corresponding movement of the handle. 115

8. A safety switch mechanism comprising a switch blade movable into "on" and "off" 120 positions, a contact for the switch blade, an operating handle for the switch blade, connections between the operating handle and the switch blade whereby to move the switch blade in response to the movements of the handle and which permit independent 125 movement of the handle with respect to the connections, said connections including a pawl for engaging the operating handle adapted to produce movement of said connections by movement of the handle in one 130

direction, and an over-load control for the switch blade comprising means operable first to disengage the pawl from the handle, and then to operate said connections.

- 5 9. A safety switch mechanism comprising a switch blade movable into "on" and "off" positions, a contact for the switch blade, an operating handle for the switch blade, connections between the operating handle and 10 the switch blade whereby to move the switch blade in response to the movements of the handle and which permit independent movement of the handle with respect to the connections, said connections including a pawl 15 for engaging the operating handle adapted to produce movement of said connections by movement of the handle in one direction, a movable member movable through a first stage to disengage the pawl from the handle, 20 and through a second stage to operate said connections, and means to move said movable member.

10. A safety switch mechanism comprising a switch blade movable into "on" and 25 "off" positions, a contact for the switch blade, an operating handle for the switch blade, connections between the operating handle and the switch blade whereby to move the switch blade in response to the 30 movements of the handle and which permit independent movement of the handle with respect to the connections, said connections including a pawl for engaging the operating handle adapted to produce movement of 35 said connections by movement of the handle in one direction, a movable member movable through a first stage to disengage the pawl from the handle, and through a second stage to operate said connections, an over-load 40 coil, and means associated therewith for moving said movable member.

11. A safety switch mechanism comprising a switch blade movable into "on" and "off" positions, a contact for the switch blade, an 45 operating handle for the switch blade, connections between the operating handle and the switch blade whereby to move the switch blade in response to the movements of the handle and which permit independent movement of the handle with respect to the connections, said connections including a pawl 50 for engaging the operating handle adapted to produce movement of said connections by movement of the handle in one direction, 55 said connections also including a toggle, a member pivotally connected to one link of said toggle, and means to move said member about its pivot for disengaging said pawl from said handle, and said last mentioned 60 means being adapted also to thereafter move said member with said link to operate the toggle.

12. A safety switch mechanism comprising a switch blade movable into "on" and "off" 65 positions, a contact for the switch blade, an

operating handle for the switch blade, connections between the operating handle and the switch blade whereby to move the switch blade in response to the movements of the handle and which permit independent movement of the handle with respect to the connections, said connections including a pawl for engaging the operating handle adapted to produce movement of said connections by movement of the handle in one direction, 70 said connections also including a toggle, a member movable relatively to one link of said toggle for disengaging said pawl from said handle, means for so moving said member and for also moving said link to operate the 80 toggle.

13. A safety switch mechanism comprising a switch blade movable into "on" and "off" positions, a contact for the switch blade, an operating handle, toggle links between the 85 operating handle and the switch blade which permit of independent movement of the handle with respect to the toggle links, a pawl engaging between the operating handle and one of said toggle links in a manner to prevent movement of the toggle in one direction except by corresponding movement of the operating handle, and means to disengage the pawl and to move the toggle in said direction.

14. A switch mechanism comprising a switch blade, a toggle mechanism, an operating handle having means to break the toggle, a pawl for connecting the handle to the toggle mechanism, and other means to break 100 the toggle irrespective of the movement of the handle, said handle being so disposed in frictional engagement with the toggle mechanism that the operating handle is moved into an intermediate position upon the 105 breaking of the toggle.

15. A safety switch mechanism comprising a switch blade movable into "on" and "off" positions, a contact for the switch blade, an operating handle movable into "on" and "off" 110 positions for producing "on" and "off" movements respectively of the switch blade, other means for producing "off" movement of the switch blade, and means coöperative to move the operating handle to an intermediate position upon operation of said mentioned other means.

16. A switch mechanism comprising a base board, a face plate spaced from the base board, a switch blade in the space between 120 the base board and the face plate, an operating handle for the switch blade projecting through the face plate, connections between the operating handle and the switch blade, and a support for the operating handle comprising a supporting brace of U-shape secured to the base board and having its ends provided with means for attaching the face plate thereto.

17. A switch mechanism comprising a base 130

- board, a face plate spaced from the base board, a switch blade in the space between the base board and the face plate, an operating handle for the switch blade projecting through the face plate, connections between the operating handle and the switch blade, supporting means for the switch blade extending between the base board and the face plate to also support the face plate, and a support for the operating handle comprising a supporting brace extending between and attached to the base board and the face plate.
18. A switch mechanism comprising a base board, a face plate spaced from the base board, a switch blade in the space between the base board and the face plate, an operating handle for the switch blade projecting through the face plate, connections between the operating handle and the switch blade, wall members defining an inclosure for the switch blade between the base board and the face plate, a pair of wall members extending between the face plate and

the base board spaced apart and serving to support the switch blade in the space between them, and said last mentioned wall members being spaced from the first mentioned wall members so as to define passageways separated from said switch blade for the purpose set forth.

19. A switch mechanism comprising a movable contact member, an operating handle, a toggle mechanism operatively connected to the contact member and in frictional engagement with the operating handle whereby movement of the toggle mechanism causes movement of the handle, and a pawl for operatively connecting the toggle mechanism to the operating handle whereby the toggle mechanism is positively actuated thereby.

In testimony whereof I affix my signature in the presence of two witnesses.

HUBERT F. KRANTZ.
